PISTON

Wilhelm Krämer, Neckarsulm, Wurttemberg, Germany, assignor to American Lurgi Corporation, New York, N. Y., a corporation of New York

Application November 27, 1939, Serial No. 306,421
In Germany November 2, 1938

8 Claims. (Cl. 309—11)

The present invention relates to pistons, and particularly to pistons having oval elastic skirts.

Pistons having oval elastic skirts have been heretofore utilized in internal combustion engines. In such pistons, as a rule, the eyelets in which the wrist pin is mounted have been connected by suitable ribs with the head and the annular part of the piston below the head. When such a piston is heated, as it is by the explosion of the fuel in the cylinder, the high temperature of the piston head is transmitted to the skirt and the wrist pin eyelets and deforms the skirt so that it becomes more or less circular in cross section. In such pistons the skirt is usually separated partially from the piston head by a slot located in a plane transverse to the cylinder axis, to permit such deformation.

A great disadvantage of the prior art has been that in pistons of this type the deformation is so great that after high heating the skirt upon cooling does not resume its former oval shape, but retains a rounder shape. In other words, the piston exceeds its elastic limits in the expansion and therefore its skirt does not return to its oval form. Obviously this results in a poor fit of the skirt within the cylinder.

The problem is particularly grave in the case of light metal pistons. These metals are especially subject to the disadvantage of failing to return to their original shape upon cooling, when they have been distorted by heat. In such pistons it has been found that the skirt cannot be properly supported and that the wrist pin eyelets are likely to assume an inclined position and thus to give improper support to the wrist pin. This is even more true in the case of pistons in which a rib perpendicular to the piston head or parallel to the cylinder axis is provided between the piston head and the eyelet for the wrist pin. Such a construction deforms the skirt to a great extent and thus renders the piston unsatisfactory.

The primary object of the present invention is to provide a piston which in use does not undergo a permanent deformation from its original oval form. It has been found that, if the amount of deformation is limited in some manner so that it does not exceed 50% of the normal deformation at present experienced, this deformation is sufficient when heated to provide the necessary play in the engine cylinder, and at the same time to avoid any permanent deformation so that upon cooling the piston returns to its original shape. This keeps the wrist pin in proper position in the cylinder, and at the same time elimi-

nates the rubbing of the lower portion of the skirt against the cylinder walls which occurs if too great a deformation takes place.

A further object of the present invention is to provide a light metal piston in which a special construction limits the deformation of the skirt and prevents deformation thereof beyond the elastic limit of the material.

A further object of the invention is to provide a light metal piston in which these results are accomplished by providing a connecting bar or strap across the piston, parallel to and close to the wrist pin, to connect opposing sides of the skirt. This strap is so located that it reaches a temperature somewhere between those of the piston head and the piston skirt. In such a manner the strap expands less than the head, so that the expansion of the piston skirt is thereby limited.

The invention is preferably applied to a piston having an uninterrupted skirt, which is of course simple to manufacture since the cutting of slots therein parallel to the cylinder axis is unnecessary. Also it is applied preferably to a piston which in at least some of the planes through the cylinder axis presents a continuous surface. While slots may be provided in planes transverse to the cylinder axis, in the annular part of the piston adjacent the cylinder head, these slots do not extend completely around the piston, and particularly do not extend around the piston in the plane which contains the wrist pin axis.

Further objects and advantages of the invention will appear more fully from the following description, particularly when taken in conjunction with the accompanying drawing which forms a part thereof.

Fig. 1 shows in cross section through the wrist pin axis a piston embodying one form of the invention;

Fig. 2 is a cross section on the line II—II of Fig. 1;

Fig. 3 is a view similar to Fig. 1 of a modified form of the invention;

Fig. 4 is a cross section on the line IV—IV of Fig. 3.

The piston as shown in Figs. 1 and 2 includes a piston head 2 below which is an annular portion 4. Downwardly extending from the annular portion 4 is the continuous skirt 6. The wrist pin receiving openings 8 are provided in projections or bosses 10 of the skirt. In order to permit deformation of the skirt when heated, there are provided in the annular portion 4 horizontal slots 12, these slots being located so that they

do not intersect the plane in which the axis of the wrist pin receiving holes 8 lies, so that in this plane the lateral surface of the piston skirt and annular portion is uninterrupted. The piston is of course hollow, and is preferably formed of any well known light metal or light metal alloy.

In the form shown, as will be apparent from a careful inspection of the drawing, the piston is of oval form, its dimension transverse to the 10 wrist pin axis being slightly greater than its dimension parallel to this axis. Fig. 2 clearly shows this difference in dimensions when compared with Fig. 1.

A piston so constructed would have the disadvantage that upon expansion of the parts thereof the skirt might expand in the direction of the arrows 14 of Fig. 1, and thus change the oval shape of the piston to a more nearly circular shape. If this deformation exceeds a certain amount, the piston will not return to its normal oval shape upon being cooled again. To avoid such great expansion, there is provided a connecting strap 16 which extends across from one side of the piston to the other, parallel to and just above the bosses 10 of the wrist pin openings. In the form shown in Figs. 1 and 2, this strap is integral with the piston body. The strap is not heated as highly as the head, although it will be heated more than the skirt. It will thus limit the expansion caused by the piston head, on the skirt, since it will hold the skirt outwardly against the forces exerted by the highly heated piston head.

In some types of engines, as for instance in air cooled Diesel engines, the piston head is subjected to very great heat. Under these conditions it may sometimes happen that the strap 16 will be inadequate to limit the expansion of the skirt sufficiently, since it will be heated to so great a temperature that it will not prevent excess deformation of the skirt, even though its temperature may be less than that of the head. The form of the invention shown in Figs. 3 and 4 avoids even this disadvantage. In this case instead of utilizing a strap integral with the head there is used a strap of a material having a lower coefficient of expansion than the material of the piston body. In the case of light metal alloys, for example, this connecting member may be of steel.

The piston shown in Figs. 3 and 4 has a head, annular member, skirt and wrist pin bosses and openings similar to those of Figs. 1 and 2. However it is provided just above the wrist pin bosses with openings having countersunk outer ends. Through these openings extends a tie member or tie rod 18, the ends of which are upset as at 20 in the countersunk openings. This tie rod thus rigidly connects together the two sides of the piston, except as it may expand slightly when heated. Any other suitable tie member might be used.

By carefully selecting the material of which such a tie rod is made, with a view to its particular coefficient of expansion, it is possible to utilize such a construction to control as desired the variations in the shape of the skirt so as to obtain any desired effect.

While I have described herein some embodiments of my invention I wish it to be understood that I do not intend to limit myself thereby except within the scope of the appended claims.

I claim:

1. A light metal piston for internal combustion 75

engines comprising a head, an annular part extending from said head, and a skirt of oval cross section extending below said annular part, said piston having a slot therein located in a plane transverse to the longitudinal axis of the piston between the annular portion and the skirt, said skirt having means to receive a wrist pin and means, symmetrical with respect to the longitudinal plane of the piston containing the axis of the wrist pin receiving means, and parallel to the axis of said wrist pin receiving means, connecting the opposite sides of said skirt, said last means comprising a strap of a material having such a coefficient of expansion as to prevent deformation of the skirt beyond a predetermined amount when the piston is subjected to a predetermined temperature.

2. A light metal piston for internal combustion engines comprising a head, an annular part extending from said head, and a skirt of oval cross section extending below said annular part, said piston having a slot therein located in a plane transverse to the longitudinal axis of the piston between the annular portion and the skirt, said skirt having means to receive a wrist pin, and means, symmetrical with respect to the longitudinal plane of the piston containing the axis of the wrist pin receiving means, and above said wrist pin receiving means and extending parallel to the axis thereof, connecting the opposite sides of said skirt, said last means comprising a strap of a material having such a coefficient of expansion as to prevent deformation of the skirt beyond a predetermined amount when the piston is subjected to a predetermined temperature.

3. A piston for internal combustion engines formed of light metal and comprising a head, an annular portion extending from said head, and a skirt extending from said annular portion, 40 said skirt having wrist pin receiving means, said annular portion and skirt being of greater diameter in a direction transverse to the axis of said wrist pin receiving means than in a direction parallel to the axis of said wrist pin receiving means, a slot located in a plane transverse to the longitudinal axis of the piston partially separating said annular portion from said skirt, the piston skirt being circumferentially uninterrupted, and means, symmetrical with respect to the longitudinal plane of the piston containing the axis of the wrist pin receiving means, and extending parallel to the axis of said wrist pin receiving means, connecting the opposite sides of said skirt.

4. A piston for internal combustion engines formed of light metal and comprising a head, an annular portion extending from said head, and a skirt extending from said annular portion, 50 said skirt having wrist pin receiving means, said annular portion and skirt being of greater diameter in a direction transverse to the axis of said wrist pin receiving means than in a direction parallel to the axis of said wrist pin receiving means, a slot located in a plane transverse to the longitudinal axis of the piston partially separating said annular portion from said skirt, the lateral face of said piston being substantially uninterrupted in a plane including the axis of said wrist pin receiving means, the piston skirt being circumferentially uninterrupted, and means, 60 symmetrical with respect to the longitudinal plane of the piston containing the axis of the wrist pin receiving means, and extending parallel to the axis of said wrist pin receiving means, connecting the opposite sides of said skirt.

5. A piston for internal combustion engines formed of light metal and comprising a head, an annular portion extending from said head, and a skirt extending from said annular portion, said skirt having wrist pin receiving means, said annular portion and skirt being of greater diameter in a direction transverse to the axis of said wrist pin receiving means than in a direction parallel to the axis of said wrist pin receiving means, a slot located in a plane transverse to the longitudinal axis of the piston partially separating said annular portion from said skirt, the lateral face of said piston being substantially uninterrupted in a plane including the axis of said wrist pin receiving means, the piston skirt being circumferentially uninterrupted, and means, symmetrical with respect to the longitudinal plane of the piston containing the axis of the wrist pin receiving means, and extending parallel to the axis of said wrist pin receiving means, and located thereabove connecting the opposite sides of said skirt.

6. A piston for internal combustion engines formed of light metal and comprising a head, an annular portion extending from said head, and a skirt extending from said annular portion, said skirt having wrist pin receiving means, said annular portion and skirt being of greater diameter in a direction transverse to the axis of said wrist pin receiving means than in a direction parallel to the axis of said wrist pin receiving means, a slot located in a plane transverse to the longitudinal axis of the piston partially separating said annular portion from said skirt, and means, symmetrical with respect to the longitudinal plane of the piston containing the axis of the wrist pin receiving means, and extending parallel to the axis of said wrist pin receiving means, connecting the opposite sides of said skirt, said last means comprising a member formed of a material having a different coefficient of expansion from the light metal of the piston.

7. A piston for internal combustion engines formed of light metal and comprising a head, an annular portion extending from said head, and a skirt extending from said annular portion, said skirt having wrist pin receiving means, said annular portion and skirt being of greater

5 diameter in a direction transverse to the axis of said wrist pin receiving means than in a direction parallel to the axis of said wrist pin receiving means, a slot located in a plane transverse to the longitudinal axis of the piston partially separating said annular portion from said skirt, the lateral face of said piston being substantially uninterrupted in a plane including the axis of said wrist pin receiving means, the piston skirt being circumferentially uninterrupted, and means, symmetrical with respect to the longitudinal plane of the piston containing the axis of the wrist pin receiving means, and extending parallel to the axis of said wrist pin receiving means and located thereabove, connecting the opposite sides of said skirt, said last means comprising a member formed of a material having a different coefficient of expansion from the light metal of the piston.

8. A piston for internal combustion engines formed of light metal and comprising a head, an annular portion extending from said head, and a skirt extending from said annular portion, said skirt having wrist pin receiving means, said annular portion and skirt being of greater diameter in a direction transverse to the axis of said wrist pin receiving means than in a direction parallel to the axis of said wrist pin receiving means, a slot located in a plane transverse to the longitudinal axis of the piston partially separating said annular portion from said skirt, the lateral face of said piston being substantially uninterrupted in a plane including the axis of said wrist pin receiving means, the piston skirt being circumferentially uninterrupted, and means, symmetrical with respect to the longitudinal plane of the piston containing the axis of the wrist pin receiving means, and extending parallel to the axis of said wrist pin receiving means and located thereabove, connecting the opposite sides of said skirt, said last means comprising a member formed of a material having a different coefficient of expansion from the light metal of the piston such as to prevent deformation of the skirt beyond a predetermined amount when the piston is subjected to a predetermined temperature.
